UNITED STATES PATENT OFFICE

136,556

DESIGN FOR A SUCTION SYRINGE

Paul W. Saunders, Tarpon Springs, Fla., assignor to Saunders Venom Extractor Company, Tarpon Springs, Fla., a partnership consisting of Jesse A. Clement, Tarpon Springs, Fla., (Mrs.) Starr C. Kibbee, Mitchell, S. Dak., and Paul W. Saunders and Fred B. Saunders, both of Tarpon Springs, Fla.

Application June 22, 1943, Serial No. 110,503

Term of patent 14 years

To all whom it may concern:

Be it known that I, Paul W. Saunders, a citizen of the United States, residing at Tarpon Springs, in the county of Pinellas and State of Florida, have invented a new, original, and ornamental Design for a Suction Syringe, of which the following is a specification, reference being had to the accompanying drawing, forming part thereof.

Figure 1 is a perspective view of a suction syringe embodying my new design;

Figure 2 is a top plan view thereof; and

Figure 3 is a bottom plan view thereof.

I claim:

The ornamental design for a suction syringe, as shown.

PAUL W. SAUNDERS.
